UNITED STATES PATENT OFFICE.

CHARLES BERTRAND SIMMONS, OF BRISTOL, CONNECTICUT, ASSIGNOR TO ISRAEL S. BAILEY, OF SOUTHBINGTON, CONNECTICUT.

FOLDING DRAWING-KNIFE.

1,400,382.

Specification of Letters Patent. Patented Dec. 13, 1921.

Application filed June 27, 1921. Serial No. 480,724.

To all whom it may concern:

Be it known that I, CHARLES BERTRAND SIMMONS, a citizen of the United States, residing at Bristol, in the county of Hartford and State of Connecticut, have invented certain new and useful Improvements in Folding Drawing-Knives, of which the following is a specification.

My invention relates to improvements in folding drawing knives, and the objects of my improvement are simplicity and economy in construction, and efficiency and convenience in use.

In the accompanying drawing:—

Figure 1 is a sectional side elevation of my folding drawing knife with one of the handles partly folded or turned toward the blade.

Fig. 2 is a sectional edge view of the same, the plane of section being indicated by the line 2—2 of Fig. 1 and the point or direction of the view being indicated by the dart in the said Fig. 1.

Fig. 3 is a broken side elevation of the shank and head at one end of the drawing knife with attached spring latch, the handle and handle ears being removed.

A, designates the blade from the ends of which the shanks 4 project, the said shanks terminating in substantially circular heads 5 which are truncated upon the outer edge to form the seat for the body of the spring latch 6. The heads are centrally perforated as at 7, Fig. 3, to receive the hinge pintle 8 of the handle ears 9, 10. Each pair of handle ears is formed of two pieces of sheet metal with substantially circular heads centrally perforated to receive the pintle 8, and offset sidewise to bring their shanks 11 together while their heads are spaced properly to receive between them the terminal heads 5 of the shanks 4. The handle shanks 11 may be of any desired length and width and secured together by the rivets 12, Fig. 1. The handles B are bored or recessed to receive the said shanks of the handle ears and may be secured to the said shanks by the pins or rivets 13. The said handles may be slotted as at 14, Fig. 1, to receive the cutting edge of the blade A when the handles are folded upon it as is usual in this class of drawing knives. These spring latches may be secured to the shanks 4 in any ordinary manner as for example by means of the rivets 18. The

said spring latches have a body of a width 55 that may lie within the space between handle ears of each handle while at their opposite edges the catch lugs 15 project substantially in the form of a cross as best shown in Fig. 2. The end of the spring that projects outside of the catch lugs is curved upwardly as shown to form a convenient handle 17. The circular heads of the handle ears, which are preferably of the same size as the heads 5, have notches 16 formed in their peripheral edges 60 for the catch lugs to fall into for locking the handle in the desired positions. These notches are preferably made a little the widest at their outer edge to facilitate the entry of the lugs thereto. The edge of the 65 handle ears between these notches is circular and concentric to the pintles 8. Only two pair of notches are shown in each pair of handle ears as ordinarily two positions of the handle is all that is desired.

In Fig. 1, the left hand handle is shown as locked in its working position. In order to fold the handle up against the edge of the blade for the usual purposes, the operator has but to lift the spring latch to bring the 70 catch lugs out of the notches in the handle ears and then turn the handle inwardly. The 75 spring latch may be so lifted by pressing the ball of the thumb against the handle 17 of the said latch. Upon turning the handle, 80 after the spring latch is withdrawn, the concentric faces at the edge of the handle ears come under the catch lugs so that the spring latch may be released by the operator and let the catch lugs rest on the edge of the 85 handle ears, as shown at the right hand end of Fig. 1, the handle at that end being shown at about half-way between its working and closed positions. When the catch lugs thus rest on the edge of the handle ears it is only 90 necessary to push the handle inwardly until it closes upon the blade and the proper recess comes under the catch lugs which snap into place and lock the handle in its closed or 95 folded position. Upon withdrawing the 100 catch lugs from the recesses, the handle may be turned to its working position and locked there by the spring catch as shown at the left hand end of Fig. 1.

By my improvement, the construction is 105 simple and inexpensive and the handles are locked firmly in position by simple and convenient means. I am also enabled to con-

struct the handle ears from sheet metal, whereby they may be very cheaply produced and are firm and substantial.

I claim as my invention:—

5 1. A drawing knife having the end shanks and heads with spring latches secured thereon, the said spring latches having the two catch lugs projecting from opposite edges and handle ears hinged to the said heads, 10 and having peripheral notches in the edges for being engaged by the said lugs as the spring latch falls between the ears.

15 2. A drawing knife having the end shanks and heads with spring latches secured thereon, the said latches having the two catch lugs projecting from opposite edges and a handle projecting outwardly from between the said catch lugs, and handle ears hinged to the said heads and having peripheral 20 notches for being engaged by the said catch lugs.

3. In combination in a drawing knife, a

blade having at each end a plate-like head and a blade shank intermediate said head and the blade body, a handle structure comprising a handle body and a handle shank structure, said handle shank structure being composed of two similar pieces of sheet metal positioned in opposition one to the other, said pieces having the outer ends connected with the handle body, the inner ends of said pieces being in the form of ears that are positioned in spaced relation to receive therebetween said head, said ears having notches in the peripheral edges, and a latch spring secured by one end to said blade shank, extended over said head, and provided at each side edge with a laterally extending catch lug for engaging with said notches, whereby the latch operates to simultaneously make locking engagement individually with the two sheet metal pieces of the handle structure.

CHARLES BERTRAND SIMMONS.
